UNITED STATES PATENT OFFICE.

OTTO G. WORSLEY, OF NEWARK, ILLINOIS.

ROCK-DRILL.

SPECIFICATION forming part of Letters Patent No. 681,011, dated August 20, 1901.

Application filed February 23, 1901. Serial No. 48,600. (No model.)

To all whom it may concern:

Be it known that I, OTTO G. WORSLEY, a citizen of the United States, and a resident of Newark, county of Kendall, and State of Illinois, have invented certain new and useful Improvements in Rock-Drills, of which the following is a specification and which are illustrated in the accompanying drawings, forming a part thereof.

This invention relates to percussion-drills of the class adapted more particularly for sinking well-shafts and in which there is provided a laterally-expansible cutting-blade adapted to be automatically thrown out after the drill is passed through and below the well-casing.

The objects of the invention are to secure increased strength and durability and to generally improve upon the construction of drills of this type.

The invention consists in the structure hereinafter described and as illustrated in the accompanying drawings, in which—

Figures 1 and 2 are longitudinal sections of the drill and a detail of the well-casing, showing the cutter in different positions. Fig. 3 is a detail elevation of the drill, partly in section, from a point of view ninety degrees removed from that of Figs. 1 and 2; and Fig. 4 is a detail section on the line 4-4 of Fig. 1.

The lower end of the well-casing is shown at 10 and the shoe applied thereto at 11. The stock 12 of the drill is tubular and is adapted to be secured, as shown, by means of screw-threads to a drill-rod. (Not shown.) An end cutter 13 is attached, as shown, by screw-threads to the lower end of the drill-stock. The stock is longitudinally apertured along one side, as shown at 14, and a side cutter or reamer 15, secured within the chamber of the stock, projects laterally through this aperture. The side cutter is provided with laterally-projecting stems 16 and 17, the former extending upwardly and the latter downwardly within the chamber of the stock. The stem 16 is provided at its outer end with a hook 18 for engaging a link 19, having an upwardly-projecting stem 20, around which is coiled an expanding-spring 21, which reacts between a head 22 on the outer end of the stem 20 and a cross-head 23, apertured for the accommodation of the stem 20, and having depending

legs 24 25, between which the link 19 may play and which rest upon a pin 26, set across the chamber of the stock.

The top of the side cutter 15 is flattened, so as to engage a reinforced shoulder 28, forming the upper wall of the aperture 14 of the stock. The body of the cutter 15 is provided with an inwardly-projecting boss 29, the upper end of which is beveled and is adapted to slidably engage the correspondingly-beveled lower end of an inwardly-projecting boss 30, formed upon or secured to the wall of the stock 12 opposite the aperture 14.

The tension of the spring 21 is sufficient to draw up the cutter against the friction of the contacting faces of the bosses 29 and 30, and the cutter is thereby thrown outwardly by a cam action and is drawn forcibly against the shoulder 28, the boss 29 being seated upon the boss 30 and the downwardly-projecting stem 17 lying against the opposite wall of the stock below the aperture 14. When the cutter is retracted, the boss 29 seats itself under the boss 30, the lower end of the latter forming a beveled abutment which is engaged by the upper beveled edge of the boss 29.

In use the cutter is introduced into the chamber of the stock by being inserted downwardly through the aperture 14 and its hook 18 engaged with the link 19. The link and the spring 21 and the cross-head 23, carried thereby, are then pushed up into position, and the pin, which serves as a guide for and limits the downward movement of the link, is driven in place, the legs 24 and 25 of the cross-head resting thereon. The cutter is held in its retracted position as the drill is inserted into the upper end of the casing 10 and is prevented, of course, from being thrown out or expanded so long as the cutter is within this casing. When the drill-stock has passed so far beyond the bottom of the casing 10 that the side cutter is relieved from contact therewith, it is thrown out by the action of the spring 21.

The end cutter 13 drills a hole of a diameter equal to its width, and the side cutter reams out the hole to a sufficient diameter to receive the casing 10.

The construction is such that the force of the blows struck by the cutter 15 is well distributed. As the cutter projects laterally,

the blow of course tends to tilt it, throwing its upper end back and its lower end outward, the tendency being to rock the cutter upon the bosses 29 30. The major part of the blow is resisted by the shoulder 28; but a considerable part of it is transmitted to the boss 30 and through the lower stem 17 to the opposite wall of the stock. This distribution of the force of the blows materially increases the durability of the parts.

When it is desired to withdraw the drill, it is simply necessary to apply a lifting strain to its stem, and when the upper end of the projecting portion of the cutter 15 comes into contact with the shoe 11 of the well-casing the cutter is held and the spring 21 compressed until the boss 30 has passed above the boss 29, when the latter falls into the position shown in Fig. 2, and this action is facilitated by the inclined form of the outer upper corner of the cutter 15, as shown at 32. The cutter being in its retracted position when the stock is lowered to the bottom of the well-casing, a passage is formed between the lower edge of the cutter 15 and the upper wall of the aperture 14, and unless some means were provided to close this passage mud or dirt adhering to the inner wall of the casing might be scraped into the chamber of the stock and accumulating there clog the cutter and possibly prevent it from expanding. In order to avoid this difficulty, a slide 33, located in the recess 34 on the stock, is provided for closing the passage when the cutter is retracted. Such slide is slotted and held by a pin 35, which passes through the slot in the slide and guides the same in frictional en-

gagement with the bottom of the recess, so that the slide may be maintained in the desired position without other holding means. When it is desired to remove the cutter from the stock, the slide is moved away from across the bottom of the aperture 14.

I claim as my invention—

1. In a rock-drill, in combination, a chambered stock having a lateral aperture, a cutter housed within the chamber and projecting through the aperture, and having a bearing against the top wall of the aperture, against the wall of the stock opposite the aperture, and against the wall of the stock below the aperture.

2. In a rock-drill, in combination, a chambered stock having a lateral aperture, a cutter housed within the stock-chamber and adapted to project therefrom, and having a shoulder for seating against the top wall of the lateral aperture and upwardly and downwardly projecting stems, a spring for drawing the cutter upwardly, and a boss within the stock for forcing it outwardly when moved by the spring.

3. In a rock-drill, in combination, a chambered stock having a lateral aperture, a cutter housed within the chamber and projecting through the aperture, and a slide for closing the passage between the lower wall of the aperture and the lower edge of the cutter when the cutter is in its retracted position.

OTTO G. WORSLEY.
